1-ALKYL-1,2,5,6-TETRAHYDRO-3-PYRIDYLMETHYL CARBOXYLIC

OBJECTS OF THE INVENTION

It is an object of the invention to provide the novel carboxylic acid esters of the formula I and their acid addition and quaternary ammonium salts.

It is another object of the invention to provide novel processes for the preparation of the carboxylic acid esters of the formula I.

It is a further object of the invention to provide novel spasmolytic compositions.

It is an additional object of the invention to provide a novel method of treating spasms in warmblooded animals.

These and other objects and advantages of the invention will become obvious from the following detailed description.

THE INVENTION

The novel compounds of the invention are selected from the group consisting of 1-alkyl-1,2,5,6-tetrahydro-3-pyridylmethyl carboxylic acid esters of the formula

wherein R is selected from the group consisting of alkyl of two to 10 carbon atoms optionally substituted with cyano or alkoxy of one to seven carbon atoms, branched alkyl of three to five carbon atoms, alkenyl of two to three carbon atoms optionally substituted with a halogen, alkynyl of two to three carbon atoms, cycloalkyl of three to six carbon atoms and phenyl alkyl of one to seven alkyl carbon atoms, R₁ is selected from the group consisting of hydrogen, methyl, -OH and Cl-, R₂ is selected from the group consisting of hydrogen, phenyl, cycloalkyl of five to six carbon rings and R₁ and R₂ together with the carbon to which they are attached form a five to six member cycloaliphatic ring, R₃ is phenyl and when R₂ and R₃ are each phenyl they may optionally be linked together in the orthopositions by a direct bond or through an oxygen atom and their nontoxic, pharmaceutically acceptable acid addition salts and quaternary ammonium salts.

Examples of suitable acids for the formation of the nontoxic, pharmaceutically acceptable acid addition salts are inorganic acids such as hydrochloric acid, hydrobromic acid, sulfuric acid, phosphoric acid, nitric acid, etc., and organic acids such as oxalic acid, citric acid, tartaric acid, fumaric acid, maleic acid, acetic acid, propionic acid, butyric acid, methane sulfonic acid, succinic acid, etc.

The quaternary ammonium compounds may be prepared by reacting a compound of the formula I with a lower alkyl or aralkyl halide or dialkyl sulfate. Examples of suitable agents are ethyl bromide, ethyl chloride, butyl bromide, phenethyl bromide, methane sulfonate, etc.

The novel products of the invention are preferably used in the form of their acid addition salts or quaternary ammonium salts. Examples of specific compounds of the formula I are 1-ethyl-1,2,5,6-tetrahydro-3-pyridylmethyl benzilic acid ester, 1-isopropyl-1,2,5,6-tetrahydro-3-pyridylmethyl benzilic acid ester, 1-n-butyl-1,2,5,6-tetrahydro-3-pyridylmethyl benzilic acid ester, 1-n-amyl-1,2,5,6-tetrahydro-3-pyridylmethyl benzilic acid ester, 1-isoamyl-1,2,5,6-tetrahydro-3-pyridylmethyl benzilic acid ester, 1-n-hexyl-1,2,5,6-tetrahydro-3-pyridylmethyl benzilic acid ester, 1-n-heptyl-1,2,5,6-tetrahydro-3-pyridylmethyl benzilic acid ester, 1-n-octyl-1,2,5,6-tetrahydro-3-pyridylmethyl benzilic acid ester, 1-n-nonyl-1,2,5,6-tetrahydro-3-pyridylmethyl benzilic acid ester, 1-n-decyl-1,2,5,6-tetrahydro-3-pyridylmethyl benzilic acid

ester, 1-(β -cyanoethyl)-1,2,5,6-tetrahydro-3-pyridylmethyl benzilic acid ester, 1-(β -methoxyethyl)-1,2,5,6-tetrahydro-3-pyridylmethyl benzilic acid ester, 1-cyclopropyl-1,2,5,6-tetrahydro-3-pyridylmethyl benzilic acid ester, 1-allyl-1,2,5,6-tetrahydro-3-pyridylmethyl benzilic acid ester, 1-propargyl-1,2,5,6-tetrahydro-3-pyridylmethyl benzilic acid ester, 1-phenethyl-1,2,5,6-tetrahydro-3-pyridylmethyl benzilic acid ester, 1-ethyl-1,2,5,6-tetrahydro-3-pyridylmethyl α -cyclopentyl- α -phenyl-acetic acid ester, 1-ethyl-1,2,5,6-tetrahydro-3-pyridylmethyl α -cyclohexyl- α -phenyl-acetic acid ester, 1-ethyl-1,2,5,6-tetrahydro-3-pyridylmethyl 1'-phenylcyclopentane carboxylic acid ester, 1-ethyl-1,2,5,6-tetrahydro-3-pyridylmethyl hexahydro-benzilic acid ester.

The novel carboxylic acid esters of the formula I may be produced by either of the following two procedures:

a. by esterification of a compound of the formula

II

wherein R has the above meaning and X is hydroxy or a halogen atom with a compound of the formula

III

wherein R₂, R₃ and R₁ possess the above meanings and Y is hydroxy or an alkoxy group or a metal, or with another derivative of this compound suitable for esterification, according to known methods, as described for example in Houben-Weyl, Methoden der Organischen Chemie, Vol. III, pg. 508, (1952) or

b. by alkylation of an ester of the formula

IV

wherein R₂, R₃ and R₁ have the above meanings, at the nitrogen atom of the tetrahydropyridine ring, according to known processes, as for example described in Houben-Weyl, Methoden der Organischen Chemie, Vol. XI/1, pg. 3 (1957).

The final products of the formula I can be reacted with an aqueous acid to form the corresponding acid addition salt or converted into a quaternary ammonium salt by known procedures.

The esterification of a compound of the formula II is preferably performed using a customary esterification agent, such as an acyl halide or anhydride or by reacting a compound of formula II, wherein X is a halogen atom, with a salt of a carboxylic acid of the formula III. Furthermore, the reaction of an acid ester of the formula III (Y=O-alkyl) with a carbinol of the formula II (X=OH) has proved to be especially suitable.

The compounds of the formula II used as starting materials for process (a) are also novel and they may, for instance, be produced by alkylation of a 2,3,5,6-tetrahydropyridine-3-carboxylic acid alkyl ester at the nitrogen atom and subsequent

reduction of the ester, such as with aluminum lithium hydride, or by reduction of a quaternary pyridylcarbinol of the formula

wherein R has the above meaning, by means of sodium borohydride.

The alkylation of a compound of the formula IV may be performed by all conventional methods of substitution of a hydrogen atom linked to a nitrogen atom, in the known way. Thus, for instance, a compound of the formula IV may be converted with an alkyl halide in the usual way into the compound substituted at the nitrogen atom. The novel compounds may also be obtained by reaction of a secondary amine of the formula IV with an aldehyde in the presence of formic acid.

The 1,2,5,6-tetrahydro-3-pyridylmethyl carboxylic acid esters of the formula IV used as starting materials in process (b) are also novel compounds and they may, for instance, be obtained by ester exchange of 1,2,5,6-tetrahydro-3-pyridylmethyl alcohol with an ester, preferably the methyl ester, of the desired acid of the formula III (Y=OH).

The novel spasmolytic compositions of the invention are comprised of small but effective amounts of at least one compound of the formula I or its acid additions or quaternary ammonium salts and a major amount of a pharmaceutical carrier. The compositions may be in the form of pills, tablets, sugar-coated tablets, ointments, suppositories, solutions, injectable solutions and suspensions, etc. The usual useful dose is 0.1 to 50, preferably 1 to 5 mg., and they may contain other therapeutic agents such as hypnotics or tranquilizers.

The novel compositions of the invention have spasmolytic and central sedative properties. They not only have the same degree of activity as the known spasmolytic, atropine, but they incorporate a novel type of spasmolytic activity as side effects such as mydriasis, tachycardia and partially also inhibition of secretion, at present considered as being unavoidable for such substances, are practically completely missing. In particular, they have an extraordinarily favorable ratio of the desired spasmolytic action and the undesirably mydriatic side effect. In the animal test, lacrimation and salivation remained uninfluenced as well in the applied doses.

As no tachycardia was observed as well, and as with some of the novel compounds the gastric fluid inhibiting effect of atropine is practically completely absent as well, all the undesirable side effects of atropine are nearly eliminated with the compounds according to the invention.

Among the preferred compounds of formula I proven to be especially effective, are those where R represents an alkyl group with two to six carbon atoms or allyl, R₁ is hydroxy and R₂ and R₃ are phenyl groups.

The novel method of treating spasms in warmblooded animals comprises administering to warmblooded animals a safe and effective amount of at least one compound of the formula I or an acid addition salt or quaternary ammonium salt thereof. The compounds may be administered orally, rectally or transcutaneously. The usual useful daily dose is 0,005 to 2,5 mg./kg. depending upon the mode of administration and the particular compound.

In the following examples there are described several preferred embodiments to illustrate the invention. However, it should be understood that the invention is not intended to be limited to the specific embodiments.

EXAMPLE I

PREPARATION OF

1-n-Hexyl-1,2,5,6-tetrahydro-3-

Pyridylmethyl benzilic acid ester

STEP A: 1-n-hexyl-1,2,5,6-tetrahydro-3-pyridyl-carbinol

22.5 g. (0.1 mol) of 1-n-hexyl-1,2,5,6-tetrahydronicotinic acid methyl ester (b.p.=90-95° C. at 0.01 mm. Hg) were dropped over 1 hour while stirring into a solution of 2.1 g. (0.55 mol) of LiAlH₄ in 200 ml. of absolute ether. After 2 hours of heating at reflux, the mixture was cooled off and excess LiAlH₄ was decomposed cautiously with 10 ml. of water. The mixture was centrifuged for a further hour and the ether solution was filtered. The residue was washed several times with small portions of ether and the filtrate was finally evaporated in vacuo at 40° C. maximum. The sirupy residue was distilled in high vacuo to obtain 16.5 g. (84 percent yield) of 1-n-hexyl-1,2,5,6-tetrahydro-3-pyridyl-carbinol as a colorless oil having a boiling point of 115°-120° C. at 0.5 mm. Hg.

STEP B: 1-n-hexyl-1,2,5,6-tetrahydro-3-pyridylmethyl benzilic acid ester

19.7 g. (0.10 mol) of 1-n-hexyl-1,2,5,6-tetrahydro-3-pyridyl-carbinol and 26.6 (0.11 mol) of methyl ester of benzilic acid were dissolved successively in 100 ml. of absolute n-heptane at 80° C. After addition of 1 ml. of sodium methylate solution (4.6 g. of sodium in 100 ml. of methanol), the mixture was refluxed for 2 hours and the split off methanol was recovered in the water separator. After the reesterification was finished, the solution at approx. 80° C. was filtered over activated charcoal and evaporated under the waterjet vacuo to obtain 37 g. (73 percent yield) after recrystallization from isopropyl ether of 1-n-hexyl-1,2,5,6-tetrahydro-3-pyridylmethyl benzilic acid ester with a melting point of 57°-58° C. The hydrobromide salt thereof had a melting point of 135° C., the methane sulfonate thereof had a melting point of 141°-142° C. and the bromomethylate derivative melted at 205°-206° C.

EXAMPLE Ia

109.12 g. (1 mol) of 3-pyridyl carbinol and 173.33 g. (1.05 mol) of n-hexylbromide were dissolved in 400 ml. of methanol and the solution was heated to 60° C. within a sealed vessel for 3 days. Into the solution diluted with 2.4 liters of methanol, there was added over 50 minutes at 15° C. while stirring 62.4 g. (1.65 mol) of NaBH₄. The reaction solution was stirred for 75 minutes and then evaporated in vacuo at a bath temperature of 60° C. The residue was divided between 1.5 liters of ether and 550 ml. of water and the aqueous phase was once more extracted with 500 ml. of ether. The united ether phases were filtered over coal and after drying over anhydrous Na₂SO₄, were evaporated under reduced pressure to obtain 178.3 g. (90.3 percent of theory) of crude 1-n-hexyl-1,2,5,6-tetrahydro-3-pyridylcarbinol which may be used for esterification without further purification.

EXAMPLE II

1-Isoamyl-1,2,5,6-tetrahydro-

3-pyridylmethyl benzilic acid ester

18.4 g. (0.1 mol) of 1-isoamyl-1,2,5,6-tetrahydro-3-pyridyl carbinol and 10.2 g. (0.1 mol) of absolute triethylamine were dissolved in 100 ml. of absolute benzene. While cooling externally with ice-water and stirring, a solution of 26.5 g. (0.1 mol) of α , α -diphenyl- α -chloroacetylchloride in 100 ml. of absolute benzene was added to this solution within 20 minutes. Stirring was continued for 1 hour at room temperature and the triethylammonium chloride was filtered off and the solution was evaporated in vacuo. The oil residue was boiled in 200 ml. of distilled water. After a clear solution has formed (approx. 3

minutes), it was adjusted to a pH value of 5 to 6 with 2 N hydrochloric acid, cooled and extracted several times with small portions of ether. The aqueous phase was made alkaline with sodium bicarbonate solution and extracted three times with 50 ml. of ether. After drying over K_2CO_3 , the ether was evaporated off and the resulting residue of 1-isoamyl-1,2,5,6-tetrahydro-3-pyridylmethyl benzilic acid ester was dissolved in 60 ml. of alcohol and converted with alcoholic hydrochloric acid (pH 3 to 4) into the hydrochloride salt. The alcoholic solution was filtered over activated charcoal and ether was added until the solution became turbid. 19 g. (43 percent yield) of the hydrochloride of 1-isoamyl-1,2,5,6-tetrahydro-3-pyridylmethyl benzilic acid ester having a melting point of 151°-152° C. were obtained.

EXAMPLE III

1-n-Hexyl-1,2,5,6-tetrahydro-3-pyridylmethylbenzilic acid ester methane sulfonate

32.34 g. (0.1 mol) of 1,2,5,6-tetrahydro-3-pyridylmethyl benzilate and 18.2 g. (0.11 mol) of 1-n-bromo-hexane in 75 ml. of absolute benzene were refluxed in the presence of 11.1 g. (0.11 mol) of absolute triethylamine for 5 hours and the mixture was then allowed to rest for 15 hours at room temperature. The crystallized triethylammonium bromide was filtered off and the filtrate was evaporated as far as possible under waterjet vacuo at an exterior temperature of 50° C. maximal. The residue was dissolved in 50 ml. of alcohol and the resulting solution was adjusted with methane sulfonic acid to a pH of 2. By adding ether thereto until turbidity occurred, there were obtained 31 g. (61.5 percent yield) of 1-n-hexyl-1,2,5,6-tetrahydro-3-pyridyl methyl benzilic acid ester methane sulfonate melting at 141°-142° C. The bromoethylate of the said ester had a melting point of 177°-178° C. and the bromobutylate had a melting point of 144°-145° C.

EXAMPLE IV

1-(β -Methoxyethyl)-1,2,5,6-tetrahydro-3-pyridylmethyl benzilic acid ester hydrochloride

32.3 g. (0.1 mol) of 1,2,5,6-tetrahydro-3-pyridylmethyl benzilate were dissolved in a mixture of 75 ml. of tetrahydrofuran and 30 ml. of dimethylformamide while heating to approx. 50° C. and then 16.8 g. (0.2 mol) of anhydrous sodium bicarbonate were added thereto. While stirring and heating at reflux, 15.3 g. (0.11 mol) of 2-(β -bromoethyl)-methylether, dissolved in 15 ml. of tetrahydrofuran and 6 ml. of dimethylformamide were dropped into the solution. After refluxing for 4 hours, the inorganic material was filtered off and the filtrate was evaporated as far as possible in the boiling water bath. The residue was dissolved in 300 ml. of benzene, filtered over activated charcoal and evaporated again. The residue was purified over aluminum oxide (activity step III) and then on a silica gel column, with ethyl acetate as solvent system. The eluates were evaporated under waterjet vacuo at a bath temperature of 50° C. to obtain 20.15 g. (54.4 percent of theory) of 1-(β -methoxyethyl)-1,2,5,6-tetrahydro-3-pyridylmethyl benzilic acid ester. Its hydrochloride melted at 145°-146° C.

EXAMPLE V

1-Ethyl-1,2,5,6-tetrahydro-3-pyridylmethyl- α -cyclopentyl- α -phenyl-acetic acid ester

Into a solution of 14.1 g. (0.1 mol) of 1-ethyl-1,2,5,6-tetrahydro-3-pyridylcarbinol and 10.2 g. of absolute triethylamine in 100 ml. of anhydrous benzene, a solution of 22.3 g. (0.1 mol) of α -cyclopentyl- α -phenyl-acetic acid chloride in 100 ml. of absolute benzene were dropped over 30 minutes while stirring and cooling. The solution was stirred for

another 2 hours at room temperature, and the precipitated triethylammonium chloride was filtered and the benzene solution was evaporated in vacuo. The residue was mixed with water, made weakly acidic with 2 N hydrochloric acid and extracted twice with little ether. The acid solution was made alkaline with $NaHCO_3$ and extracted with ether. The ether solution was dried over anhydrous sodium sulfate and evaporated in vacuo. The crude 1-ethyl-1,2,5,6-tetrahydro-3-pyridylmethyl α -cyclopentyl- α -phenyl-acetic acid ester was converted into its hydrochloride in the usual way and by recrystallization from acetonitrile/ether, 23 g. (63.4 percent of theory) of the analytically pure hydrochloride salt melting at 166°-168° C. were obtained.

15

6

EXAMPLE VI

Using the procedure of example I, 1-ethyl-1,2,5,6-tetrahydro-3-pyridyl methyl benzilic acid ester hydrochloride having a melting point of 163° C. was obtained.

20

EXAMPLE VII

Using the procedure of example I, 1-ethyl-1,2,5,6-tetrahydro-3-pyridylmethyl benzilic acid ester bromoethylate having a melting point of 190°-191° C. was obtained.

25

EXAMPLE VIII

Using the procedure of example I, 1-n-propyl-1,2,5,6-tetrahydro-3-pyridylmethyl benzilic acid ester hydrochloride having a melting point of 131° C. was obtained.

30

EXAMPLE IX

Using the procedure of example I, 1-isopropyl-1,2,5,6-tetrahydro-3-pyridylmethyl benzilic acid ester hydrochloride having a melting point of 167°-168° C. was obtained.

35

EXAMPLE X

Using the procedure of example I, 1-n-butyl-1,2,5,6-tetrahydro-3-pyridylmethyl benzilic acid ester hydrochloride having a melting point of 143° C. was obtained.

40

EXAMPLE XI

Using the procedure of example I, 1-n-pentyl-1,2,5,6-tetrahydro-3-pyridylmethyl benzilic acid ester hydrochloride having a melting point of 150° C. was obtained.

45

EXAMPLE XII

Using the procedure of example I, 1-n-heptyl-1,2,5,6-tetrahydro-3-pyridylmethyl benzilic acid ester hydrochloride having a melting point of 140° C. was obtained.

50

EXAMPLE XIII

Using the procedure of example I, 1-n-octyl-1,2,5,6-tetrahydro-3-pyridylmethyl benzilic acid ester hydrobromide having a melting point of 125° C. was obtained.

55

EXAMPLE XIV

Using the procedure of example I, 1-n-nonyl-1,2,5,6-tetrahydro-3-pyridylmethyl benzilic acid ester hydrobromide having a melting point of 124° C. was obtained.

60

EXAMPLE XV

Using the procedure of example I, 1-n-decyl-1,2,5,6-tetrahydro-3-pyridylmethyl benzilic acid ester hydrochloride having a melting point of 127° C. was obtained.

65

EXAMPLE XVI

Using the procedure of example I, 1-allyl-1,2,5,6-tetrahydro-3-pyridylmethyl benzilic acid ester hydrochloride having a melting point of 143°-144° C. was obtained.

70

7
EXAMPLE XVII

Using the procedure of example I, 3-chloroallyl-1,2,5,6-tetrahydro-3-pyridylmethyl benzilic acid ester hydrochloride having a melting point of 135° C. was obtained.

EXAMPLE XVIII

Using the procedure of example I, 1-phenethyl-1,2,5,6-tetrahydro-3-pyridylmethyl benzilic acid ester hydrochloride having a melting point of 172°-173° C. was obtained.

EXAMPLE XIX

Using the procedure of example I, 1-ethyl-1,2,5,6-tetrahydro-3-pyridylmethyl- α -cyclohexyl- α -phenyl-acetic acid ester hydrochloride having a melting point of 203°-204° C. was obtained.

EXAMPLE XX

Using the procedure of example I, 1-ethyl-1,2,5,6-tetrahydro-3-pyridylmethyl 1-phenylcyclopentane-carboxylic acid ester hydrochloride having a melting point of 143°-145° C. was obtained.

EXAMPLE XXI

Using the procedure of example I, 1-ethyl-1,2,5,6-tetrahydro-3-pyridylmethyl-1-phenylcyclohexane carboxylic acid ester hydrochloride melting at 186°-188° C. was obtained.

EXAMPLE XXII

Using the procedure of example I, 1- β -cyanoethyl-1,2,5,6-tetrahydro-3-pyridylmethyl benzilic acid ester hydrochloride melting at 146°-148° C. was obtained.

EXAMPLE XXIII

Using the procedure of example I, 1-propargyl-1,2,5,6-tetrahydro-3-pyridylmethyl benzilic acid ester hydrochloride melting at 142°-143° C. was obtained.

EXAMPLE XXIV

Using the procedure of example I, 1-ethyl-1,2,5,6-tetrahydro-3-pyridylmethyl hexahydrobenzilic acid ester hydrochloride melting at 210°-212° C. was obtained.

EXAMPLE XXV

Using the procedure of example I, 1-n-hexyl-1,2,5,6-tetrahydro-3-pyridylmethyl hexahydrobenzilic acid ester hydrochloride melting at 132°-135° C. was obtained.

EXAMPLE XXVI

Using the procedure of example I, 1-ethyl-1,2,5,6-tetrahydro-3-pyridylmethyl- α , α -diphenyl acetic acid ester hydrochloride melting at 198°-200° C. was obtained.

PHARMACEUTICAL EXAMPLES

Example A

Sugar-Coated Tablets

1-n-hexyl-1,2,5,6-tetrahydro-3-pyridylmethyl benzilic acid ester-HCl	5.0 mg.
lactose	28.5 mg.
corn starch	15.0 mg.
gelatin	1.0 mg.
magnesium stearate	0.5 mg.
Total	50.0 mg.

8

Preparation

The mixture of the active ingredient with lactose and corn starch was granulated with a 10 percent aqueous gelatin solution through a screen of 1 mm. mesh size, dried at 40° C. and triturated once more through a screen. The granulate thus obtained was mixed with magnesium stearate and pressed into cores. The cores thus obtained were coated with a shell in the usual manner, the latter being attached to the cores with an aqueous suspension of sugar, titanium dioxide, talcum and gum arabic. The finished sugar coated tablets were polished with beeswax to obtain sugar coated tablet weighing 100 mg.

Example B

Tablets

20	1-ethyl-1,2,5,6-tetrahydro-3-pyridylmethyl benzilic acid ester-HCl	3.0 mg.
	lactose	50.0 mg.
	corn starch	32.0 mg.
	soluble starch	4.0 mg.
	magnesium stearate	1.0 mg.
25	Total	90.0 mg.

Preparation

The active ingredient and magnesium stearate were granulated with an aqueous solution of the soluble starch. The granulate was dried and intimately mixed with lactose and corn starch. The mixture was then pressed into tablets of 90 mg. of weight, each containing 3 mg. of active ingredient.

Example C

Suppositories

40	1 suppository contains: 1-allyl-1,2,5,6-tetrahydro-3-pyridylmethyl benzilic acid ester-HCl	5.0 mg.
	suppository mass	1,695.0 mg.
	Total	1,700.0 mg.

Preparation

45 The finely pulverized active substance was stirred into the molten suppository mass cooled to 40° C. with the aid of an immersion homogenizer. At 35° C., the mass was poured into slightly precooled molds.

50

Example D

Ampuls

55	1-n-hexyl-1,2,5,6-tetrahydro-3-pyridylmethyl benzilic acid ester-HCl	2.0 mg.
	sodium chloride	18.0 mg.
	distilled water	2.0 ml.

60

Preparation

60 The active ingredient and sodium chloride were dissolved in water. The solution was filtered free of suspended particles and filled into 2 cc. ampuls under aseptic conditions. Finally the ampuls were sterilized and sealed. Each ampul contained 2 mg. of active ingredient.

Various modifications of the compositions and method of the invention may be made without departing from the spirit or scope thereof.

We claim:

70 1. A compound of the formula

wherein

R is straight alkyl of two to 10 carbon atoms, branched alkyl of three to five carbon atoms, alkenyl of two to three carbon atoms, halo-alkenyl of two to three carbon atoms, alkenyl of two to three carbon atoms, cycloalkyl of three to six carbon atoms or phenyl-(alkyl of one to two carbon atoms),

R₁ is hydrogen, methyl, hydroxyl or chlorine,

R₂ is hydrogen, phenyl or cycloalkyl of five to six carbon atoms, and

R₁ and R₂, together with each other and the carbon atom to which they are attached, are cyclopentyl or cyclohexyl, or a nontoxic, pharmaceutically acceptable acid addition salt thereof.

2. A compound according to claim 13, wherein R is alkyl of two to six carbon atoms or allyl, R₁ is hydroxyl and R₂ is phenyl.

3. A compound according to claim 13, which is 1-n-hexyl-1,2,5,6-tetrahydro-3-pyridylmethyl benzilic acid ester or a nontoxic, pharmaceutically acceptable acid addition salt thereof.

4. A compound according to claim 13, which is 1-ethyl-

1,2,5,6-tetrahydro-3-pyridylmethyl benzilic acid ester or a nontoxic, pharmaceutically acceptable acid addition salt thereof.

5. A compound according to claim 13, which is 1-n-amyl-1,2,5,6-tetrahydro-3-pyridylmethyl benzilic acid ester or a nontoxic, pharmaceutically acceptable acid addition salt thereof.

6. A compound according to claim 13, which is 1-phenylethyl-1,2,5,6-tetrahydro-3-pyridylmethyl benzilic acid ester or a nontoxic, pharmaceutically acceptable acid addition salt thereof and its quaternary ammonium salts.

7. A compound according to claim 13, which is 1-allyl-1,2,5,6-tetrahydro-3-pyridylmethyl benzilic acid ester or a nontoxic, pharmaceutically acceptable acid addition salt thereof.

15. A compound according to claim 1, wherein

R is alkyl of two to 10 carbon atoms, allyl, chloroallyl, propargyl or phenethyl,

R₁ is hydrogen or hydroxyl,

R₂ is phenyl, cyclopentyl or cyclohexyl, and

R₁ and R₂, together with each other and the carbon atoms to which they are attached, are cyclopentyl or cyclohexyl.
